UNITED STATES PATENT OFFICE.

HENRY W. MILLER, OF BROOKLYN, NEW YORK.

STRAINER.

1,139,992.

Specification of Letters Patent. Patented May 18, 1915.

Application filed August 5, 1914. Serial No. 855,125.

To all whom it may concern:

Be it known that I, HENRY W. MILLER, a citizen of the United States of America, residing at Brooklyn, in the county of Kings 5 and State of New York, have invented a new and useful Strainer, of which the following is a specification.

My invention relates to improvements in strainers for water in service or supply 10 pipes, and consists of a certain peculiar chambered casing, which is adapted to be attached to water pipes, and is provided at the bottom with a removable plug or cap, and a foraminous cylindrical member 15 mounted on a spindle that rises from said plug or cap, and supported by said spindle in the water-way through said casing, all as hereinafter set forth.

The object of my invention is to provide a 20 comparatively simple and inexpensive device for thoroughly straining foreign matter out of the water supply for a house or other building, and for catching such matter in such a manner that it can be removed easily 25 and conveniently from time to time as may be necessary or desirable. This device can be readily installed at some suitable and convenient point in the supply pipe line, and after being so installed need not be removed under ordinary circumstances or conditions.

Other objects and advantages will appear in the course of the following description.

I attain the objects and secure the advantages of my invention by the means illustrated in the accompanying drawings, in which—

Figure 1 is a central vertical section through a strainer that embodies a practical form of the invention; Fig. 2, a bottom plan of the foraminous member or strainer proper, the spindle being in section, and, Fig. 3, a top plan of the cap, the spindle here also being in section.

Similar numerals refer to similar parts throughout the several views.

The device comprises a casing 1, an inverted cap 2 from the center of which rises a spindle 3, and a perforated cylinder 4 which is mounted on the top of said spindle.

The cylinder 4 has a top 5 which is the part that is actually or directly mounted on the spindle 3, and said part may be perforated like the sides of the inverted cup 55 formed by the cylinder 4 and said part or

top. The center of the top 5 is attached to the spindle 3, and the latter thus passes through the axial center of the cylinder 4. Preferably the aforesaid cup is formed from a single piece of foraminous material, although this is not necessary, and the cylinder 4 might be supported from the spindle 3 by some other means, as will be readily understood by one skilled in the art.

Near the top of the casing 1 on one side 65 is an inlet connection 6 for attachment to a water pipe, and diametrically opposite such connection is an outlet connection 7 for attachment to a water pipe. It is by means of the connections 6 and 7 that the strainer 70 is introduced into a line of supply pipes, the connection 6 being toward the source of supply so that the water enters the casing 1 through said connection 6 and leaves said casing by way of the connection 7. A circular chamber 8 is formed in the upper end of the casing 1, into which the perforated cylinder 4 is received, said chamber preferably being larger in diameter than is said cylinder. At the top of the chamber 8 is an 75 annular shoulder 9 into which the upper terminal of the cylinder 4 is received and by which such terminal is in part supported, and at the bottom of said chamber is an annular flange 10, through which said cylinder 80 passes when placed in operative position and removed from such position, and which in part supports the lower terminal of said cylinder when in place. The construction of the upper portion of the casing 1 is such 85 that water entering said casing, through the connection 6, must, in order to escape

through the connection 7, pass upwardly through the flange 10 and the chamber 8, as will be clearly seen upon referring to 90 Fig. 1. Such being the case, it follows that the water must pass into the cylinder 4, which fits within the flange 10, and then out through the perforations in said cylinder 95 into the chamber 8, the water from said chamber passing on to the connection 7. Any and all foreign matter that may be present in the water, upon its entrance to the casing 1, and which is of such a nature that it can not pass through the perforations in the 100 cylinder 4, is caught within the latter and directly or eventually falls or is washed down into a sediment chamber 11 in said casing. Thus the supply of water between the strainer and the drawing point is freed 105 110

from foreign matter in suspension to an extent limited only by the coarseness or fineness of the mesh of which the cylinder 4 is made or of the perforations in said cylinder.

5 The cylinder top 5 prevents the foreign matter from escaping from the cylinder above and finding its way down into the chamber 8.

The base of the spindle 3 is firmly set in 10 the center of the cap 2, and said spindle rises from said cap through the sediment chamber 11. The chamber 11 increases in diameter below the bottom horizontal plane 15 of the connections 6 and 7, and the cap 2 is tapped into the open bottom of said chamber, as represented at 12. The cap 2 is made hollow in order to increase the size of the sediment chamber or to add thereto, and to 20 the same end such cap may be lengthened to 25 any reasonable extent and by any suitable means. The chamber in the cap 2, which chamber is practically a part of the chamber 11, is represented at 13. The cap 2 is here provided with an exterior flange 14 which fits into an annular groove 15 in the bottom of the casing 1. This construction assists in making a tight joint between the cap and casing, but may be changed altogether.

As occasion requires, the water is shut off 30 between the connection 6 and the source of supply, and the cap 2 is unscrewed and removed, taking with it the spindle 3 and the cylinder 4 or strainer proper. The accumulation of sediment in the chamber 13 is thus 35 taken away, and that in the chamber 11 falls out through the now open bottom of said chamber 11 or of the casing 1. The interior of the chamber 11 and the parts which have been removed are next thoroughly cleansed, 40 and then said parts are returned to place, the cap 2 being screwed tightly into the bottom of the casing, as it was before. By employing for the strainer proper an open-bottom cylinder which is uniform throughout, I provide an element which is best calculated to free itself from sediment and permits the water to flow without too much interference or retardation. The cylinder 4 should have a fairly tight fit with the flange 45 10 and the shoulder 9, but at the same time such fit must not be so tight as to interfere with the placing of said cylinder in operative position or the withdrawal of the same 50 from such position.

55 In addition to some modifications hereinbefore noted, it is to be understood that changes in the shape and size of my device, also in other features of arrangement and

construction of parts, may be made without departing from the spirit of my invention. 60

What I claim as my invention, and desire to secure by Letters Patent, is—

1. The combination, in a device of the class described, with a casing having therein an open-bottom strainer chamber, and below 65 said chamber an open bottom sediment chamber, and provided with oppositely-disposed inlet and outlet connections, said inlet connection communicating with said strainer chamber through the bottom thereof by way 70 of said sediment chamber, and said strainer chamber opening laterally into said outlet connection, of a removable closure for the bottom of said sediment chamber, a spindle 75 fixed to said closure, and a perforated cylindrical member mounted on said spindle and receivable in said strainer chamber, with the base of said member fitting the bottom opening in said strainer chamber, said spindle with said closure being the sole axial support for said member, and the arrangement of parts being such that said spindle and member come away with said closure, and said member is returned to place by the act of replacing said closure. 80

2. The combination, in a device of the class described, with a casing having therein an open-bottom strainer chamber, and below 85 said chamber an open-bottom sediment chamber, and provided with oppositely-disposed inlet and outlet connections, said inlet connection communicating with said strainer chamber through the bottom thereof by way 90 of said sediment chamber, and said strainer chamber opening laterally into said outlet connections, of a removable closure for the bottom of said sediment chamber, a vertical spindle rising from said closure and having its base permanently attached thereto, and a 95 perforated cylindrical member provided 100 with a top mounted on said spindle, the latter passing through the axial center of said member and with said closure serving as the sole support for said member, and said member being receivable in said strainer 105 chamber, with the base of said member fitting the bottom opening in said chamber, the arrangement of parts being such that said spindle and member come away with said closure, and said member is returned to place by the act which replaces said closure. 110
